UNITED STATES PATENT OFFICE,

JOSEPH F. WANGLER, OF ST. LOUIS, MISSOURI.

BOILER-FURNACE.

SPECIFICATION forming part of Letters Patent No. 470,726, dated March 15, 1892.

Application filed December 19, 1891. Serial No. 415,644. (No model.)

To all whom it may concern:

Be it known that I, JOSEPH F. WANGLER, of the city of St. Louis, Missouri, have made a new and useful Improvement in the Class of 5 Boiler-Furnace Known as Slow-Combustion or Smokeless Steam-Boiler Furnaces, in which the grate-bars are formed of a gang or series of tubes opening at their inner ends into the boiler and at their front ends into a mani- 10 folded water-chamber, through which the boiler-water when heated continuously and rapidly circulates, of which the following is a specification.

In this class of furnaces, also, the fire, instead of burning from the bottom upward, burns from the top downward, the gases and smoke from combustion passing through the live fire.

The objects which I seek to attain in this 20 improved construction are, first, to facilitate the heating of the water of the boiler by exposing more of its bulk to the direct action of the furnace-fire; second, to provide means whereby in the event of the tube-supply grate-bars becoming clogged, collapsed, or burned 25 out they may be severally and readily disconnected for the purpose of removing and replacing them; third, to provide a simple means for obtaining an updraft to expedite the building 30 of a fresh fire only, and, fourth, locating a blow-off plug-valve so as to readily and effectually blow-off. I attain these objects by the mechanism which the accompanying drawings illustrate, and in which—

35 Figure I is a front elevation of a tubular boiler with its setting and arrangement shown on line 1 1, Fig. III. Fig. II is a transverse section showing the same on line 2 2, Fig. III. Fig. III is a plan and side elevation corresponding to Figs. I and II. Fig. IV is a detail 40 section of the front water-chamber, showing pipe and nipple connection. Fig. V is a similar view showing the pipe end expanded to make a joint; and Fig. VI, a detail sectional view of the middle water-chamber, showing 45 the pipe connection therewith.

Similar letters refer to similar parts throughout the several views.

In the drawings, A represents an ordinary 50 boiler of the tubular pattern having its furnace internally constructed and integral with

it through the water-chambers and pipe-bar connections shown, namely:

B is the depending boiler-space; C, the lower inner dependent boiler-space having 55 connection with the space B by perpendicularly-arranged pipes e' e'.

D is the front water-chamber connected at its ends to the lower front part of the boiler A by the leaders E E and connected at its 60 inner side by the slightly-inclined horizontal pipes e e to the space C, and through said last-mentioned space to the boiler A at the depending portion B thereof through the pipes e' e', the circulation of the water through this 65 system being indicated in the drawings by the direction of the feathered arrows. The usual size of the pipes e e' is about one and one-half inches inside measurement, and they are made with a thick shell to better resist 70 the action of the fire carried on the horizontal tubes.

The pipe-nipple i, Figs. IV and V, is provided with a male and female screw-thread, the former for screwing it in the water-space 75 D and the latter to receive the inner end of the horizontal tube-bars e e. The latter after it receives the nipple is expanded, so as to make a close joint with the shoulder e' and the inner end of the nipple i inside the space 80 D. The opposite end of the pipes e e are screw-fitted with a long thread to fit into the manifold of the space C and allow room for releasing the inner end of the pipe e from its connection with the nipple i, in the manner 85 shown.

f³ represents the rear wall of the fire-box F. It is provided with an opening about its middle to admit of having an upward draft to the chimney when a fresh fire is being 90 started in the furnace, said opening being closed as soon as the fire is under good headway by the damper X (shown by dotted lines in Fig. I) and kept closed thereafter. The wall f³ is composed of fire-brick or refractory 95 tiling and is supported upon the inner ledge of the water-chamber C.

G represents the furnace-bridge, f the furnace-feed door, and f' the door of the ash-pit, the furnace-door f being provided with small 100 openings to admit air to the fire. Otherwise the fire-box F is closely built above and on

the sides and remains so, except when the damper X is opened on starting the fire, thus providing a downdraft, the flue being below the grate and the products of combustion 5 finding egress up the chimney in the direction indicated by the unfeathered arrows.

d, d', d^2 , and d^3 is the blow-off apparatus located at one end of the water-chamber D, at the lowest point in the construction, through 10 which the boiler-water circulates, and therefore conveniently adapted to blow off the impurities in the pipes, water-chambers, and boiler and cleanse the same.

The pipes e' receive the heat of the fire 15 directly it leaves the fire-box F, and together with the water-chamber C, similarly acted upon, affords good facilities for quickly heating the water by offering a direct action of the heat to the body of water contained therein.

I am aware that downdraft boiler-furnaces 20 provided with water-chamber and tube grate-bar connections with a boiler are not new. I therefore make no broad claim thereto; but

What I do claim as new, and desire to secure by Letters Patent, is—

25 In a downdraft and water-pipe grate-furnace of a boiler, the combination of the depending water-chambers B C D with the horizontal and perpendicular pipes ee' , the former being connected at their forward end by a 30 nipple, thus affording means for adjusting or readjusting the said pipes, substantially in the manner shown and described, and for the purpose specified.

JOSEPH F. WANGLER.
